UNITED STATES PATENT OFFICE.

NICOLAS GUNTURIZ, OF SAGUA LA GRANDE, CUBA, ASSIGNOR TO GUNTURIZ & CARABALLO, OF SAGUA LA GRANDE, CUBA, A PARTNERSHIP CONSISTING OF NICOLAS GUNTURIZ AND ANTONIO M. CARABALLO.

COCOANUT-PUNCH.

1,277,308.

Specification of Letters Patent. Patented Aug. 27, 1918.

Application filed December 24, 1917. Serial No. 208,667.

To all whom it may concern:

Be it known that I, NICOLAS GUNTURIZ, a citizen of the Republic of Cuba, residing at Sagua la Grande, in the province of Santa Clara and Republic of Cuba, have invented 5 certain new and useful Improvements in Cocoanut-Punches; and I do hereby declare the following to be a full, clear, and exact description of the invention, such as will 10 enable others skilled in the art to which it appertains to make and use the same.

This invention relates generally to a hand operative cutting tool and more particularly relates to a punch for punching cocoanuts.

15 It is one of the objects of the present invention to provide a practical simple and inexpensive device for the punching of cocoanuts or various other purposes in which the punch may be practically used, and

20 Another object of the present invention is to provide a punch in the form of a hammer comprising a plurality of readily detachable or removable parts to facilitate the renewal or re-adjustment of the parts as may be 25 necessary.

It is another object of the invention to 30 provide a hand operative tool whereby punchings may be made with great rapidity and the cuttings easily ejected from the cutting tool.

With these and other objects in view, the invention consists in the whole, the construction, and details and arrangement of parts as more fully hereinafter described one embodiment of the invention being illustrated in the accompanying drawing in which:

Figure 1 is a perspective view of the device.

Fig. 2 is a sectional detail view through 40 the assembled parts, and

Fig. 3 shows in perspective certain of the disassembled parts.

In the embodiment of the invention here shown, the tool comprises a handle 2 of 45 suitable proportions and which may be made of wood or any other suitable material, this carrying at one end a hammer-like head 3 which is provided at one side with a socket portion 4 to receive the handle. The head 50 is longitudinally bored at 5 to receive a slidable ejecting pin 6 which may have a head 7 at its upper end and is threaded at its lower end 8 to receive a removable eject-

ing disk 9 through which there may be passed, as shown, the threaded adjacent end 55 8 of the pin to aid in securing the disk 9 to the pin to prevent accidental separation of these elements.

The lower end of the hammer-like head is shown as exteriorly threaded at 11 for connection with a detachable annular cutter 12, the lower end of which is suitably knife-edged as at 13 to facilitate cutting of the material into which it may be driven when the head is swung by means of its handle 60 to carry the cutter with the necessary momentum into the article or object to be cut or punched. The tubular body portion 12 of the cutter is shown as somewhat enlarged at its upper end at 14 and is internally 65 threaded to engage the threads 11 of the head 3. The ejecting disk 9 is of the diameter to freely work in the chamber of the cutter 12 and the length of the pin 6 is such that the cuttings will be readily ejected from 70 the cutter by a downward movement of the pin 7 by the application of force to the pin-head 7.

From the foregoing it will be seen that 75 the present device may be utilized with great efficiency and rapidity to punch cuttings from the object or material being worked upon and enables the ready clearance of the cuttings from the cutter.

It is understood that the various metallic 80 elements may be of any suitable material and properly proportioned and designed within the principle of the present invention and that various alterations may be resorted to within the limits of the appended claims. 90

What I claim is:

1. A cocoanut punch of the nature of a hammer, comprising a head having a handle receiving socket extending laterally therefrom, and a handle in said socket an annular 95 hollow cutter at one end of the head, and an ejector having a stem sliding in said head with an enlarged ferrule in the cutter for dislodging cuttings from the chamber of the cutter.

2. A cocoanut punch comprising a head having a handle extending laterally therefrom, an annular detachable hollow cutter at one end of the head, and an ejector having a stem sliding in said head for dislodging 100 cuttings from the chamber of the cutter,

the stem having a tappet head on its end above the head and having a ferrule threaded on its inner end.

3. A cocoanut punch comprising a head having a handle attached thereto, an ejector pin working axially in the head, an annular hollow cutter at the lower end of the head, and a disk attached to said pin and circumferentially fitting, and for ejecting 10 cuttings from, the cutter.

4. A cocoanut punch comprising a head having a laterally extending handle, receiving socket, and a small axial bore and a threaded neck, a tubular cutter threaded on 15 the neck of the head, and an ejector pin extending through the head and having an enlarged end disk operative in said cutter.

5. A cocoanut punch comprising a head having a laterally extending handle, a tubu-

lar cutter threaded onto one end of the head, 20 and an ejector pin extending through and beyond the head and operative in said cutter and having transverse stop shoulders at each end.

6. A cocoanut punch consisting of a tool 25 of the nature of a hammer comprising a momentum body or head having a lateral handle whereby it may be wielded with swinging blows, the head centrally bored from end to end, a stem in said bore having a stop at 30 its upper end and an ejecting disk on its lower end, and a cylindrical cutter on the striking end of the head in which cutter the disk reciprocates, the cuttings being forced into the cutter when the device is used and 35 ejected by the ejector.

In testimony whereof I affix my signature.
NICOLAS GUNTURIZ.
